UNITED STATES PATENT OFFICE

2,111,438

GRATE

Ira C. Smith, Scranton, Pa.

Application April 20, 1937, Serial No. 138,045

6 Claims. (Cl. 126—176)

This invention relates to furnace grates generally; and particularly to oscillatory grates adapted for use with automatic stoker mechanism.

The main object of the invention is to provide a mounting for a grate of the type disclosed in my United States application Serial No. 95,463, filed August 11, 1936, and allowed January 4, 1937; and in which the grate is normally inclined to the horizontal in such manner as to provide for the automatic feed and even distribution of coal from a magazine arranged at the upper end thereof.

A further object of the invention is to provide a grate of the character described with mechanism for oscillating the grate as a whole about its lower end, while at the same time rotating the bars of the grate to cut from the fire bed the ashes and debris which ordinarily interfere with the efficient operation of the furnace.

Other objects of the invention will become apparent as the detailed description thereof proceeds.

In the drawings:

Figure 1 is a fragmentary vertical section through a furnace provided with a grate of the character described and arranged in the furnace to receive coal from a magazine feed chamber;

Figure 2 is a section taken on the line 2—2 of Figure 1;

Figure 3 is a vertical section taken on the line 3—3 of Figure 2;

Figures 4, 5, 6, and 7 are longitudinal sections of the grate illustrating the positions of the grate with respect to the magazine during a complete oscillatory movement about its lower axis;

Figure 8 is a section taken on the line 8—8 of Figure 4; and

Figure 9 is a section on the line 9—9 of Figure 1.

Referring to the drawings, in which similar parts are designated by like numerals:

The reference numeral 9 designates a furnace provided with a fuel magazine 10, and a combustion furnace chamber 11. The magazine 10 is provided with the bottom wall 12, inclined downwardly toward the combustion chamber 11 to feed fuel by gravity onto the grate designated generally by the reference numeral 13.

The grate 13 comprises a frame having side bars 14 and 15 connected at one end by a cross bar 16, and near their other ends by a cross bar 17. The side bars 14 and 15 project beyond the cross bar 17; and their projecting ends have a shaft 18, journaled therein. One end of the shaft 18 projects through the side bar 14 to seat rotat-

ably in a U-shaped bracket 19, suitably secured to the side wall 20 of the furnace 9.

The other end of the shaft 18 projects through the side bar 15 of the grate and through an aperture 21 formed in the side wall 22 of the furnace, 23 the aperture 21 forming a journal bearing for the shaft 18. A series of shafts 23 are journaled parallel to each other and to the shaft 18 in slots 24 formed in the side bars 14 and 15. One end of each shaft 23 is reduced to form a shoulder 25, seating against the inside of the side bar 14. The reduced end 26 fits within the slot 24, and is locked rotatably in the said slot 24 by means of a locking bar 27, provided with a series of slots 28, fitting over the reduced ends 26 of the shafts 23. The rear end of the locking bar 27 is apertured to fit the shaft 18, about which it may be rotated into and out of locking position with respect to the reduced ends 26 of the shafts 23. When the locking bar 27 is in locking position, it may be secured in such position by means of the screws 29.

A locking bar 30 similar in every respect to the locking bar 27 is rotatably mounted on the other end of the shaft 18 and is adapted to be 25 similarly secured in locking rotation to the side bar 15 by means of the screws 31. The shafts 23 project through arcuate slots 32 formed in the side wall 22 to provide for a somewhat limited oscillation of the grate 13 as a whole about the 30 axis of shaft 18. The free end of the grate is supported, by means of a pair of cams 33 fixed to the outer shaft 23 and resting upon brackets 34, suitably secured to the side walls 20 and 22 of the furnace.

The parallel shafts 23 are each provided with a series of spaced apart fire-supporting members 35, the members on one shaft being staggered with respect to those on the adjacent shaft or shafts. The shaft 18 has secured thereto a pair 40 of sprockets 36 and 37, and a crank handle 38. The sprockets 36 and 37 are operatively connected by means of sprocket chains 38' and 39 to sprockets fixed to the ends of the parallel shafts 23, so as to rotate all of said shafts simultaneously and in the same direction.

It will be obvious from inspection of the drawings and when the shaft 18 is rotated by means of the crank 38 all the shafts 23 and the fire supporting members arranged thereon will be 50 simultaneously rotating to effect a cutting operation on the ashes or lower layer of the superposed fire bed. During the rotation of the shaft 23 the cams 33 will also be rotated, and by contact with their supporting bracket 34 will cause 55

the free end of the grate 13 to swing toward and from the downwardly inclined bottom wall 12 of the magazine 10.

The cross bar 16 is provided with a series of lugs 40 adapted to receive tongues 41 which project downwardly from a cut-off bar 42 detachably mounted on the upper edge of the bar 16 and shaped to swing across and close to the end of the bottom plate 12 of the magazine 10. The oscillatory movements of the grate 13 about its pivot shaft 18, is illustrated in Figures 4, 5, 6, and 7 of the drawings. Figure 4 shows the normal raised position of the grate 13. When the shafts 23 are rotated anti-clockwise, as shown in the drawings, the grate drops from the normal position shown in Figure 4 to the lowered position shown in Figure 5. This preliminary movement serves to break the crust formed by the fire bed. Continued anti-clockwise rotation of the shafts 23 moves the grate from the position shown in Figure 5 to that shown in Figure 6 in which the scoop-like fingers of the fire supporting members 35 are in vertical position.

It will be noted that the upper end of the cut-off bar 42 projects above the downwardly inclined bottom wall 12 of the magazine, when the grate is positioned as shown in Figure 6. The cams 33 are substantially circular between the radii 43 and 44 so that further anti-clockwise rotation of the cams through an angle of about 90°, will produce very little movement of the grate section 35 with respect to the bottom plate 12 of the magazine. Further anti-clockwise movement from the position shown in Figure 6, through that shown in Figure 7, to its normal position shown in Figure 4, merely effects a slight rocking movement which facilitates the scooping action of the members 35 on the ashes constituting the lower part of the fire bed.

It will be evident from inspection of Figures 4 to 7, inclusive, that rotation of the pivot shaft 18 not only causes rotation of all the shafts 23, with their fire supporting members 35, but also causes a decided drop from the position shown in Figure 4 to that shown in Figure 5, to cause a break in the superposed fire bed. This break, accompanied by continued rotation of the fire supporting members 35 insures an effective removal of the ashes from the fire bed, and a dropping thereof into the ash pit.

The staggered relation of the fire-supporting members 35 on each shaft with respect to the positioning of these members on adjacent shafts enhances the draft through the fire-bed, and increases the efficiency of ash removal from the fire bed. The bar 42 at the upper end of the grate is also provided with apertures 45 which serve as draft apertures for the fire bed and also as passageways for ashes which may be shaken from the fire bed by the oscillation of the grate as a whole.

Numerous variations may doubtless be devised by persons skilled in the art without departing from the principles of my invention. I, therefore, desire no limitations to be imposed on my invention, except such as are indicated in the appended claims.

What I claim is:

1. A furnace comprising a casing partitioned to form a furnace chamber and a magazine for fuel, a grate comprising a substantially rectangular frame pivoted at one end of said chamber, a plurality of shafts journaled parallel to each other in said frame, fire supporting members spaced apart along each of said shafts and ar-

ranged in staggered relation with respect to the fire supporting members on adjacent shafts, and cooperating means on said casing and grate for simultaneously rotating said shafts and for oscillating said grate to cause the free end thereof to reciprocate with respect to said magazine. 5

2. A furnace comprising a casing partitioned to form a furnace chamber and a magazine for fuel, a grate comprising a substantially rectangular frame pivoted at one end of said chamber, a plurality of shafts journaled parallel to each other in said frame, fire supporting members spaced apart along each of said shafts and arranged in staggered relation with respect to the fire supporting members on adjacent shafts, supports on the opposite side walls of said chamber for the free end of said grate, cams secured to the shaft nearest said free end and resting upon said supports, and means on said casing and shafts for simultaneously rotating said shafts and for oscillating the free end of said grate with respect to said magazine. 10

3. A furnace comprising a casing partitioned to form a furnace chamber and a magazine for fuel, a grate having a substantially rectangular frame pivoted at one end to the opposite side walls of said chamber, a plurality of shafts journaled parallel to each other in said frame, fire supporting members spaced apart along each of said shafts, means for supporting the free end of said 15 grate to maintain the grate normally inclined to the horizontal, said magazine having a bottom wall inclined to the horizontal and projecting into said furnace chamber, and cooperating means on said casing and said shafts for simultaneously rotating said shafts and for causing the free end of said grate to swing past the projecting end wall of said magazine. 20

4. A furnace comprising a casing partitioned to form a furnace chamber and a magazine for fuel, a grate having a substantially rectangular frame pivoted at one end to the opposite side walls of said chamber, a plurality of shafts journaled parallel to each other in said frame, fire supporting members spaced apart along each of 25 said shafts, means for supporting the free end of said grate to maintain the grate normally inclined to the horizontal, said magazine having a bottom wall inclined to the horizontal and projecting into said furnace chamber, and cooperating means on said casing and said shafts for simultaneously rotating said shafts and for causing the free end of said grate to swing past the projecting end wall of said magazine. 30

45

5. A furnace comprising a casing partitioned to form a furnace chamber and a magazine for fuel, a grate having a substantially rectangular frame pivoted at one end to the opposite side walls of said chamber, a plurality of shafts journaled parallel to each other in said frame, fire supporting members spaced apart along each of 45 said shafts, means for supporting the free end of said grate to maintain the grate normally inclined to the horizontal and projecting into said furnace chamber, said magazine having a bottom wall inclined to the horizontal and projecting into said furnace chamber adjacent the free end of said frame, a cutting section detachably connected to the free end of said frame and adapted to swing with said frame with respect to the projecting end of said bottom wall, and means connected to said casing and shafts for simultaneously rotating all of said shafts and for oscillating the free end of said frame to swing said cutting section toward and from the projecting end of said bottom wall. 50

6. A furnace comprising a casing partitioned to form a furnace chamber and a magazine for fuel, a grate having a substantially rectangular frame pivoted at one of its ends in said chamber, said magazine having a bottom wall inclined to 55 the horizontal and projecting downwardly into said furnace chamber, a plurality of shafts journaled parallel to each other in said frame and having fire supporting members spaced apart thereon, and cooperating means on said casing and shafts for simultaneously rotating said shafts and for oscillating the grates so that its free end swings past the downwardly projecting end of said bottom wall. 60

7. A furnace comprising a casing partitioned to 70

5 form a furnace chamber and a magazine for fuel, a grate having a substantially rectangular frame pivoted at one of its ends in said chamber, said magazine having a bottom wall inclined to the horizontal and projecting downwardly into said furnace chamber, a plurality of shafts journaled parallel to each other in said frame and having fire supporting members spaced apart thereon, supporting brackets extending from op-

posite side walls of said chamber, cams fixed to one of the shafts remote from the pivoted end of said frame and resting upon said brackets, a cutting section projecting upwardly from the free end of said frame and adapted to swing past the inwardly projecting end of said bottom wall, and gearing for simultaneously rotating said shafts and cams. 5
